UNITED STATES PATENT OFFICE.

NICHOLAS C. BOHR, OF BOSTON, MASSACHUSETTS, ASSIGNOR, BY MESNE ASSIGNMENTS, TO THOMAS G. PLANT, OF BOSTON, MASSACHUSETTS.

HEEL-SCOURER GUARD.

No. 883,445.

Specification of Letters Patent. Patented March 31, 1908.

Application filed August 30, 1907. Serial No. 390,721.

To all whom it may concern:

Be it known that I, NICHOLAS C. BOHR, a citizen of the United States, residing in Boston, in the county of Suffolk and State 5 of Massachusetts, have invented an Improvement in Heel-Scourer Guards, of which the following description, in connection with the accompanying drawings, is a specification, like letters on the drawings representing 10 like parts.

The invention to be hereinafter described relates to scouring machines for boots and shoes, and more particularly to the guard for heel scourers.

15 The object of the present invention is to provide a simple and efficient device for protecting the upper or other portion of a boot or shoe from injury during the scouring or preliminary finishing operation of the heel 20 thereof. As well known by those skilled in the art, the heel portions of boots and shoes, as part of the finishing operation, are subjected to the abrading or scouring action of a suitable element, such as an emery or other 25 rough surfaced wheel, and that as the boot or shoe is turned to bring all portions of the heel into operative relation to the scouring element or wheel, the upper or sole of the shoe is liable to be injured by contact with 30 the scourer, particularly as the edge of the heel joining the breast and exterior heel contour is approached. This is true at the beginning of the operation when the operator places the heel in position with the toe of the 35 shoe preferably pointing upward, but at such times the operator can gage the shoe position by the eye and touch so as to overcome the difficulty. As the toe of the shoe is turned downward, however, to bring the opposite 40 side and edge of the breast line into operative relation with the scourer, it frequently happens that some portion of the shoe in front of the toe contacts with the scourer, resulting in injury to the shoe, as is well 45 understood by those skilled in the art, the present invention being designed to overcome this defective action of the scourer and resulting injury to the work.

The invention will best be understood 50 from the following detail description and accompanying drawings, which present one form or embodiment of the invention for illustrative purposes without, however, restricting the invention to such details, its 55 scope being definitely pointed out in the claims.

In the drawings:—Figure 1 is a front elevation of one form of scourer with the present invention applied thereto. Fig. 2 is a cross section on line $x-x$, Fig. 1. Fig. 3 is 60 an enlarged detail showing the scouring wheel and guard in operative relation. Fig. 4 is a detail sectional view on line $y-y$, Fig. 3. Fig. 5 is a detached detail of the hinged arm of the guard bracket, looking in the 65 direction of the arrow, Fig. 3.

The standard A, the head B carrying the scouring shaft 1, the hood 2 covering the shaft driving wheel or other element, and the deflector 3, may be of any usual or desired 70 character and associated for the particular work to be done.

Mounted upon the shaft 1, are the scouring wheels 4, 4, two being shown assembled on the one shaft, but, obviously, the number 75 of such wheels is immaterial, and said wheels may be formed of any desired character of abrading material.

In scouring the heels of boots and shoes, the operative usually presents the heel to the 80 scouring wheel with the toe of the shoe pointing upward and commences the scouring action on the side of the heel at the breast line, as indicated by dotted lines in Fig. 2. At such time the operative, looking down in 85 about the general direction of the arrow, Fig. 2, can place the side of the heel properly against the scouring wheel 4, and, by the eye, so gage the position of the shoe that the upper or sole will not contact with the scouring 90 wheel. As the shoe is turned from the dotted to the full line position in Fig. 2 to bring all portions of the heel into working contact with the scouring wheel, the wheel and shoe obstruct the view of the operative, so that as 95 the final portions of the heel adjacent the breast line are reached the forepart of the shoe, usually the upper, is liable to strike or contact with the revolving scouring wheel.

As one embodiment of means for overcoming this objection, a guard is provided by the present invention, which is so disposed with relation to the working portion of the wheel, that as the shoe is turned to complete the work on the heel, the forepart will contact 105 with the guard and arrest further turning movement of the shoe.

In the form of guard selected for exploitation of the invention, a bracket arm 5 is secured to the head B by suitable means such 110 as the bolts 6, said bracket arm being provided at its end adjacent the scouring wheel

4, with a rigid portion 7, having a slot 8. Connected to the rigid portion 7 of the bracket arm by suitable means, such as the screw bolts 9, is the adjustable guard plate 10. This 5 guard plate has a protecting portion 11 extending over the peripheral surface of the scouring wheel 4, so as to effectually cover the same, and the forward edge 12 (Fig. 3) of the protecting portion 11 is preferably turned 10 or thinned off so as to bring its outer surface as close as possible to the scourer 4 and thus allow a greater range of turning movement to the shoe before the forepart contacts with the forward edge 12. By this expedient, as 15 will be readily understood by those skilled in the art, the operative is enabled to present all parts of the heel to the action of the scourer, and turn the shoe sufficiently to finish the scouring at the breast line of the heel without liability of injuring the forepart of the shoe.

In the scouring of heels of different sizes or kinds of boots and shoes it is necessary to adjust the guard plate 10 so that the protecting portion 11 will extend more or less about the scourer 4; and indeed this adjustment is desirable even with different operatives on the same kinds or sizes of shoes, because different operatives will use different portions 25 of the scouring wheel 4, some using a portion nearer to the top and some a portion nearer the bottom. In either event, the guard plate 10 is readily adjustable by simply loosening the bolts 9 moving it to the position 30 desired, and then setting the bolts.

The bolts 9 and their clamping action may be of any desired character, but in the drawings they are shown as having one end secured to the side flange of the guard plate 10 40 as at 13, the other end being extended through the curved slot 8 of the bracket arm and provided with a screw thread for the clamp nuts 14, 14.

It is sometimes desirable to move the guard 45 plate and its adjuncts to one side either for cleaning, removal of the scourer 4, or other purpose, so that the present invention, while not restricted to a two part jointed bracket arm, embraces a construction, such as shown, 50 wherein the bracket arm 5 is formed of two parts joined together by a hinge or like device, as indicated at 15, Figs. 3 and 5. In such construction one member of the bracket arm 5 is preferably provided with a stop 16 55 to prevent the outer member of the bracket arm which carries the guard plate from being moved into contact with side of the scourer 4. Likewise to hold the outer member in proper operative relation with the scourer 4. 60 a catch or lock 17 is pivoted at 18 and provided with wings 19, whereby it may be turned either into the position indicated in Fig. 3 to lock the hinged members of the bracket arm in proper relation for the guard 65 plate 10 to perform its guarding function, or

upward at substantially right angles to such position, as will be readily understood by those skilled in the art, to unlock the bracket arm members and permit the outer arm to be swung to one side.

When the catch or lock 17 is in position as indicated in Fig. 3, a stop 20 limits its turning movement by contact with a projection 21 extending from the catch or lock 17.

In describing the invention, the operative 75 has been presumed to commence the scouring action upon the heel with the toe of the shoe pointing upward, and gradually turning the toe downward from the dotted to the full line position, Fig. 2, and this is, in fact, the 80 usual method of procedure; but, obviously, the invention is not circumscribed by such limitations, its essential being that it shall be so disposed with relation to the scourer, that as the shoe approaches a position calculated 85 to bring the fore-part into contact with the scourer, the guard will act to prevent such contact.

It will be noted that the portion 7 of the bracket arm and the flange of the guard plate 10 substantially parallel thereto, protect the side of the scourer 4, so that no part of the shoe can contact with this portion of the wheel.

What I claim is:—

1. In a machine for scouring the heels of boots and shoes, the combination of a scouring wheel, a bracket arm, a guard carried by said bracket arm and having a protecting portion extending circumferentially about said scouring wheel, said bracket arm and guard being provided the one with a curved slot and the other with clamping bolts to permit adjustment, said protecting portion having its end disposed in the path of movement of a shoe as it is turned to present the heel to the action of the scouring wheel and acting as a stop in its various positions of adjustment.

2. In a machine for scouring the heels of boots and shoes, the combination of a scouring wheel, a bracket arm having a rigid portion adjacent said scouring wheel, a guard plate supported by said rigid portion and having a protecting portion extending circumferentially about said scouring wheel and means for adjusting the protecting portion with respect to the rigid portion and in a direction circumferentially about the said wheel to present said protecting portion in the path of movement of a shoe as it is turned to subject the heel to the scouring action of said wheel.

3. In a machine for scouring the heels of boots and shoes, the combination of a scouring wheel, a guard plate disposed about a portion of said scouring wheel and extending over the scouring wheel in the path of movement of a shoe as it is turned to subject the heel to the scouring action of said wheel, said

guard plate terminating in a turned or thinned outer edge to permit maximum turning movement of the shoe and a support for said guard plate.

5. 4. In a machine of the character described, the combination of a scouring wheel, a guard plate extending about a portion of said wheel, and having side and face protecting portions 10 and 11 for said scouring wheel, a support 10 for said guard plate, and means for adjustably connecting the guard plate and support to enable the former to be moved in a curved path to cover different portions of the scouring wheel in accordance with the work being done.
15. 5. In a machine of the character described, the combination of a scouring wheel, a guard plate having a protecting portion extending circumferentially of the scouring wheel and provided with a turned or thinned edge 12, a support for said guard plate, and means for adjusting the guard plate about the scouring wheel to cover different portions thereof.
20. 6. In a machine of the character described, the combination of a scouring wheel, a bracket arm formed of members hinged to-

gether, a guard plate carried by one of said members and extending about a portion of said scouring wheel, and means for adjusting the guard plate to cover different portions of said scouring wheel as desired. 30

7. In a machine of the character described, the combination of a scouring wheel 4, a bracket arm 5 having a portion 7, a guard plate 10 adjustably connected to said portion 35 7 and having a protecting portion 11, substantially as described.

8. A heel scouring machine comprising, in combination, a scouring wheel 4, a guard plate 10 having a protecting portion 11 extending about said scouring wheel 4, said protecting portion having a thinned edge 12, a support for said guard plate and means for connecting the support and guard plate. 40

In testimony whereof, I have signed my 45 name to this specification, in the presence of two subscribing witnesses.
